UNITED STATES PATENT OFFICE.

JOSEPH BUCHEK, OF OAK PARK, ILLINOIS.

DESIGN FOR A LOCK.

50,773.

Specification for Design.

Patented May 15, 1917.

Application filed November 27, 1916. Serial No. 133,820. Term of patent 3½ years.

To all whom it may concern:

Be it known that I, JOSEPH BUCHEK, a subject of the Emperor of Austria-Hungary, residing in Oak Park, in the county of Cook and State of Illinois, have invented a new, original, and ornamental Design for a Lock, of which the following is a specification, reference being had to the accompanying drawing, forming part thereof.

Figure 1 is an illustration showing a side elevation of my new ornamental design for a lock;

Fig. 2 illustrates an end elevation of same; Fig. 3 a plan view.

I claim:

The ornamental design for a lock as shown.

In witness whereof, I have hereunto subscribed my name this 18th day of November, 1916.

JOSEPH BUCHEK.
